UNITED STATES PATENT OFFICE

2,466,581

GEOGRAPHICAL GLOBE

Benjamin H. Darrow, Columbus, Ohio

Application September 10, 1947, Serial No. 773,220

8 Claims. (Cl. 35—46)

1

The present invention relates generally to educational devices and is particularly concerned with a novel globe which is readily and economically constructed and easily used.

It has long been customary to make terrestrial globes without means attached thereto for measuring distances on the globes. In instances where such means have been provided, they are normally attached to a globe-supporting fitting at the North Pole, for instance, and are in the form of tapes which are permitted to lie on the globe or hang therefrom when not in use. Such tapes are quickly soiled and in such condition present an unpleasant appearance and detract from the appearance and diminish the utility of the globe, and are consequently not generally used.

By virtue of my invention it is now, for the first time to my knowledge, possible to attach to a globe measuring means which will not detract from the appearance of the globe despite soiling and wear, and will not substantially reduce the useful surface area of the globe or diminish its utility. Furthermore, in accordance with this invention such measuring means may be provided at a small cost, the parts comprising the means in any of its several forms being readily and cheaply obtainable. In any of its several forms, in fact, the means of my invention is readily installed, requires no maintenance and is fully automatic insofar as removal of the means from sight after each use is concerned. A further advantage of my invention includes the adaptability of the measuring means to use on maps applied to globes as zipper skins, for instance, which skins are provided with apertures to permit passage of measuring means therethrough. Furthermore, the globes of this invention may be produced at very small cost compared to globes of the same size which are presently available on the market.

Those skilled in the art will gain a further understanding of the nature of this invention and manner in which it may be used by referring to the drawings accompanying and forming a part of this specification, in which

Figure 1 is a view in section of a terrestrial globe embodying one form of this invention; and

Figure 2 is a view partly in section of another terrestrial globe equipped with means of this invention and carrying a detachable map.

The globe of Fig. 1 comprises two hemispherical sections 10 which are joined together and secured to supporting means including a table or base 11 carrying a shaft 12, and a frame 13 removably

2

and rotatably secured to said shaft. The shaft is removably secured to base 11 and extends upwardly therefrom approximately 23½ degrees from vertical and through an aperture in the lower portion (South Pole) of the globe. Frame 13, comprising a hub 14 carrying a spring pressed ball 15 in a central aperture and four equally spaced radial arms or beams 16 extending outwardly from the hub, is disposed within the globe, 5 receiving the upper end portion of shaft 12 in the aperture of hub 14 with ball 15 engaging the necked portion of the shaft and resiliently opposing relative movement of the shaft and frame lengthwise of said shaft. In addition, the globe is provided with an aperture at the North Pole defined by a grommet 17 and another aperture near the equator defined by a grommet 18, and with means disposed within the globe for measuring distances on its outer surface.

20 The measuring means in one form comprises a calibrated tape 20 having an end portion extending through grommet 17, a ring 21 secured to said end portion, and a reel 23 carried by a bracket 25 welded to one of the arms of frame 25 13 and provided with a spring 26 for rotating the reel and drawing the tape within the globe or maintaining the tape taut, as illustrated in Fig. 1. In another form, which is also illustrated in Fig. 1, the measuring means again 30 comprise a calibrated tape 27 having an end portion extending through grommet 18, a ring 28 secured to said end portion, a weight 29 attached to the other end of tape 27 within the globe, and a bracket 30 welded to one of the arms of frame 13 and having an aperture in its upper end through which the tape is threaded thus to maintain the tape as shown in Fig. 1, or to withdraw the tape into the globe after use.

35 Tapes 20 and 27 are preferably of cloth or durable, transparent, substantially inelastic but flexible synthetic resin, such as ordinary methyl methacrylate polymer, and are so dimensioned as to pass readily through grommets 17 and 18. Since a weight retractor cannot automatically 40 retract the tape its full length I prefer the spring reel type of retractor which enables the use of tape of effective length substantially greater than necessary to completely encircle the globe.

45 Hemispherical sections 10 may be of any suitable material, such as metal or papier mache, but I prefer that they be spun aluminum for convenience in assembling the globe without externally marking the globe. Grommets 17 and 18 ought not to be substantially abrasive to, or 50 abradable by, the tapes, and are preferably of

hard rubber or synthetic resin having good wearing qualities. If metal tapes are used, the grommets preferably should be of metal.

Referring to Fig. 2, a globe G similar to that shown in Fig. 1 is provided with a skin map M which has apertures 32 appropriately spaced for registry with the apertures of the globe. Apertures 32 are sufficiently large to permit handles 33 secured to the outer ends of the tapes to pass therethrough in order that the tapes may be moved over the surface of the skin. Map M is a single piece, preferably of cloth but suitably of synthetic resin which is inelastic but flexible like cloth, having zipper tracks 35 secured to its two edge portions and a zipper lock 36 carried by one of said tracks. This globe is also composed of two hemispherical sections 38, but these are of papier mache or equivalent material, and have interlocking edges 39, the upper hemisphere having a slightly smaller diameter than the lower one and overlapping a portion of the edge of the lower one around its circumference. The globe is not provided with internal bracing means such as beams 16 but has a reel 23 for retracting measuring tape 30 secured to the lower hemisphere by studs (not shown). Also unlike the Fig. 1 globe, this one is mounted on a saucer-shaped platform 40 of papier mache or equivalent material shaped to engage a portion of the spherical surface of the globe. That is, the upper surface of the platform or base is concave and of substantially the same radius as that of the globe, and has a substantially plane bottom surface to engage a table top or similar plane surface.

The globes of this invention may be provided in several parts for assembly by students to assist their understanding of the construction of the globes and of the geographical relationships between various portions of the globe, and also to minimize the expense of the globes. For instance, table 11, shaft 12 and hemispheres 10 may be furnished as individual elements, and the frame 13, brackets 25 and 30, and reel 23 may be provided as a sub-assembly. Using the foregoing basic parts, the globe may be constructed, as illustrated in Fig. 1, by placing the lower hemisphere in the position shown with shaft 12 extending through the aperture in the lower part of said hemisphere, fitting frame 13 on the upper end of the shaft so that ball 15 engages a necked portion of the shaft near its upper end. Tapes 20 and 27 are then secured in position in engagement with reel 23 and bracket 30, respectively, threaded through grommets 17 and 18, and engaged with rings 21 and 28, as illustrated. The hemispheres are then secured together and pressed into firm and fastening engagement with the ends of arm 17. The second globe may likewise be readily assembled, the steps in this case involving simply engaging the edges 39 thereof as shown, after fixing tapes 20 and 27 in place.

Map M may be applied to the finished globe by placing the map on the globe with apertures 32 in registry with the apertures defined by grommets 17 and 18, and closing the zipper tracks with lock 36 so that said lock is disposed adjacent to the South Pole aperture of the globe, leaving an opening through which shaft 12 passes.

Other maps M may be substituted for the first one or applied to the globe over said first one, if they are sufficiently large.

Having thus described the present invention so that those skilled in the art may be able to understand and practice the same, I state that

what I desire to secure by Letters Patent is defined in what is claimed.

What is claimed is:

1. An educational device comprising a hollow globe having an aperture, means for measuring distances on said globe, and means for automatically retracting said measuring means into said globe through said aperture and retaining said means therein when not in use.
- 5 2. An educational device comprising a hollow globe having an aperture, flexible means for measuring distances on said globe, means for automatically retracting said measuring means into said globe through said aperture and retaining said means therein when not in use, and means for preventing retraction of said flexible means beyond a predetermined point.
- 10 3. An educational device comprising a hollow globe having an aperture, means for measuring distances on said globe, and means for automatically retracting said measuring means into said globe through said aperture and retaining said means therein when not in use, said measuring means comprising a calibrated flexible tape, and said automatic means comprising a spring within the globe secured to the globe and to said tape.
- 15 4. An educational device comprising a hollow globe having an aperture, a flexible calibrated tape for measuring distances on said globe, and means for automatically retracting said measuring means into said globe through said aperture and retaining said means therein when not in use, said automatic means comprising a weight within the globe and secured to said tape.
- 20 5. An educational device comprising a hollow globe model of the earth having an aperture, a map on the globe depicting the earth and having an aperture in register with the aperture of said globe, and having a slide fastener to facilitate application of the map to the globe, a calibrated, flexible tape disposed partially within said globe for determining distances on the globe, means including a spring in the globe secured to the globe and tape for automatically retracting the tape into the globe through said aperture and retaining said tape therein when not in use, and means connected to the end portion of the tape outside the globe for preventing said portion from being drawn into the globe by the action of said spring.
- 25 6. An educational device comprising a hollow rotatably mounted globe having a plurality of apertures defined by small metal eyelets, a plurality of means for measuring distances on said globe, and a plurality of means for automatically retracting said measuring means into said globe through said apertures and retaining said means therein when not in use, said measuring means comprising flexible calibrated tapes.
- 30 7. An educational device comprising a hollow globe having an aperture and comprising two hollow papier mache hemispheres having interlocking edges, means for measuring distances on said globe, means for automatically retracting said measuring means into the globe through said aperture and retaining said means therein when not in use, and means supporting the globe comprising a saucer-shaped papier mache base having an upper concave surface of radius substantially the same as the radius of the globe and a lower surface to engage a substantially plane surface.
- 35 8. An educational device comprising a hollow body to support a map and having a small aperture for registry with an aperture in the map,

flexible means within the body and extending through said aperture therein for measuring distances on the map, means within the body for automatically retracting said measuring means into said body through said aperture and retaining the measuring means therein when not in use, and means outside the body associated with

the measuring means for limiting the extent of retraction of the measuring means into the body, said limiting means comprising an element too large to pass through said aperture in the body.
